SPLITTER VANE CONSTRUCTION FOR GAS VALVES

Andrew Kalitinsky, Oak Ridge, Tenn., assignor to United Aircraft Corporation, East Hartford, Conn., a corporation of Delaware

Application May 15, 1947, Serial No. 748,174

8 Claims. (Cl. 251—119)

1

This invention relates to valves and particularly to valves of the reed type.

In this type of valve the gas passage through the valve base communicates with a U-shaped slot in which a similarly shaped valve is placed to close the gas passage. The valve is clamped at its base against the valve seat by a splitter vane which permits the valve to bend away from the seat for gas to flow through the gas passage. It has been found advantageous to have the valve clamped resiliently as in the co-pending application of Ward, Serial No. 520,070, filed January 28, 1944, now Patent No. 2,496,834, in which the splitter vane has resilient ears contacting with the clamping rings that hold the splitter vane in place. A feature of this invention is an arrangement of the splitter vane such that the resilient clamping action takes place between the valve and the splitter vane rather than between the splitter vane and the clamping rings. Another feature is the provision of resilient clamping fingers on the splitter vane for engagement directly with the valve.

A feature of this invention is the provision of rugged clamping ears with the resiliency necessary in a multiple valve assembly provided by a resilient connection between each splitter vane and the associated valve.

Other objects and advantages will be apparent from the specification and claims, and from the accompanying drawings which illustrate an embodiment of the invention.

Fig. 1 is an elevation view of a set of valves.

Fig. 2 is a sectional view on the line 2—2 of Fig. 1.

Fig. 3 is a sectional view on the line 3—3 of Fig. 1.

Fig. 4 is a perspective view of the splitter vane.

Fig. 5 is a sectional view corresponding to Fig. 3 showing a modification.

As best shown in Figs. 1 and 2, the valve base 10 is mounted in a supporting structure consisting of spaced annular rings 12 and 14 which may be integrally connected together as by a series of webs 15. The valve base is positioned between these two rings and has projecting flanges 16 and 18 engaging shoulders 20 and 22 provided by the supporting structure.

The valve base has a number of annular grooves 24 extending inwardly from one side surface thereof which intersect with U-shaped slots 23 positioned radially and extending inwardly from the other side surface of the valve base. The intersecting slots form gas passages 26 extending through the base for the flow of air therethrough.

2

The gas passages are closed by U-shaped valves 30 positioned in the slots 26 as shown in Fig. 3. The valves are held in position by splitter vanes 32, the lower edges of which have slots 34 forming spaced projecting ribs or fingers 36 which clamp the valve securely in the base of the slots. The ribs are normally parallel as shown in Fig. 4 and move resiliently toward one another as the splitter vane is pressed into clamping position.

It will be understood that the splitter vane is of such a shape, as shown in Fig. 3, that the outer free edges of the valve may move away from the walls of the slot and against the splitter vane to open the gas passages for a flow of air through the valve base.

The set of splitter vanes which hold the valves in position are clamped in place by clamping rings 38 and 39 which engage with ears 40, projecting rigidly from opposite ends of the splitter vane.

As shown in Fig. 3, these ears or lugs 40 are integral with the splitter vane and are long enough to extend over and engage with the outer and inner surfaces of the valve base to limit the endwise movement of the splitter vanes. The clamping rings 38 and 39 close the ends of the slots 26 and engage with the entire set of lugs on the splitter vanes. The rings may be threaded as indicated in Fig. 2 so that the rings may be screwed down tightly against the splitter vanes,

thereby holding the vanes securely against the bases of the valves and clamping the valves securely against the valve base. The clamping rings also function to hold the flanges 16 and 18 on the valve base in secure engagement with the shoulders 20 and 22 on the supporting structure.

It will be understood that the resiliency provided by the ribs 36 adjusts for any non-uniformity resulting from manufacturing tolerances and assures that each valve will be securely clamped in position.

Instead of the integral resilient flanges on the splitter vane, as in Figs. 3 and 4, the splitter vane may have special resilient strips 42 mounted thereon, as by rivets 44, as shown in Fig. 5. The splitter vane 46 is otherwise of the same construction as the splitter vane 32 and functions to hold a valve 30 in place within the valve base 10. It has been found, in lightweight valve structures, that a magnesium or aluminum splitter

vane might not have sufficient inherent resiliency, so that it would be desirable to use separate strips of a material having a higher elasticity to provide the resilient clamping action for the valve.

It is to be understood that the invention is not limited to the specific embodiment herein illustrated and described, but may be used in other

ways without departure from its spirit as defined by the following claims.

I claim:

1. A multiple valve assembly including a base having U-shaped slots therein, gas passages through said base and intersecting said slots, a U-shaped valve in each slot for closing the ends of the gas passages, a splitter vane in each slot engaging with the base of the valve for holding the valve in place, each vane having resilient fingers along the edge engaging with the base of the valve, and each vane also having integral rigid lugs at each end projecting beyond the end of the slots, and clamping means engaging simultaneously with a series of said rigid lugs for holding the attached splitter vanes in position.

2. A multiple valve assembly including a base having U-shaped slots therein, gas passages through said base and intersecting said slots, a U-shaped valve in each slot for closing the ends of the gas passages, a splitter vane in each slot engaging with the base of the valve for holding the valve in place, each vane having resilient fingers along the edge engaging with the base of the valve, and each vane also having integral rigid lugs at each end projecting beyond the end of the slots, and being wide enough to extend over and engage with the base to restrict endwise movement of the valve, and clamping means engaging simultaneously with a series of said rigid lugs for holding the attached splitter vanes in position.

3. A multiple valve assembly including a base having U-shaped slots therein, gas passages through said base and intersecting said slots, a U-shaped valve in each slot for closing the ends of the gas passages, a splitter vane in each slot engaging with the base of the valve for holding the valve in place, each vane having resilient fingers along the edge engaging with the base of the valve, and each vane also having integral rigid lugs at each end projecting beyond the end of the slots, and clamping elements at the ends of the base to close the ends of the slots and engaging with the clamping lugs for holding the vanes in position.

4. A valve assembly including a base having a U-shaped slot therein, a gas passage through said base and intersecting said slot, a U-shaped valve in said slot for closing the end of the gas passage and a splitter vane fitting within said valve with one edge of said vane engaging and clamping the base of said valve in the base of the slot, the clamping edge of the vane having spaced resilient clamping fingers engaging with said valve, said vane having integral rigid lugs at opposite ends to extend beyond the ends of the slot, and clamping means at the ends of the base engaging with said lugs.

5. A valve assembly including a base having a U-shaped slot therein, a gas passage through said base and intersecting said slot, a U-shaped valve in said slot for closing the end of the gas passage and a splitter vane fitting within said valve with one edge of said vane engaging and clamping the base of said valve in the base of the slot, the clamping edge of the vane having spaced resilient clamping fingers engaging with said valve, said vane having integral rigid lugs at opposite ends to extend beyond the ends of the slot, and clamping means at the ends of the base en-

gaging with said lugs, said lugs being wider than the width of the slot to extend over and engage with the valve base at the ends of the slot.

6. A valve assembly including a base having a U-shaped slot therein and also having a gas passage therethrough intersecting said slot, and a U-shaped valve in said slot for closing the end of said gas passage, in combination with a splitter vane for holding the U-shaped valve in the slot by engaging with the base of the valve and holding it against the valve base, said splitter vane including a plate adapted to fit within said valve, said plate engaging and clamping the base of said valve in the base of said slot, the clamping edge of said vane being grooved to provide spaced resilient clamping flanges engaging with said valve throughout the length of the valve base, and clamping means for holding said vane in clamping position within the slot in the base.

7. A valve assembly including a base having a U-shaped slot therein and also having a gas passage therethrough intersecting said slot, and a U-shaped valve in said slot for closing the end of said gas passage, in combination with a splitter vane for holding the U-shaped valve in the slot by engaging with the base of the valve and holding it against the valve base, said splitter vane including a plate adapted to fit within said valve, with one edge of said plate engaging and clamping the base of said valve in the base of said slot, the clamping edge of said plate having resilient plates mounted thereon and spaced in substantially parallel relation to each other for engagement with said valve throughout the length of the valve base for holding it resiliently in position, and clamping means for holding said vane in clamping position within the slot in the base.

8. A valve assembly including a base having a U-shaped slot therein and also having a gas passage therethrough intersecting said slot, and a U-shaped valve in said slot for closing the end of said gas passage, in combination with a splitter vane for holding the U-shaped valve in the slot by engaging with the base of the valve and holding it against the valve base, said splitter vane including a plate adapted to fit within said valve, with one edge of said plate engaging and clamping the base of said valve in the base of said slot, the clamping edge of said plate having spaced resilient fingers extending substantially the entire length of the clamping edge of the splitter vane to engage with the base of the valve for substantially its entire length, and clamping means for holding said vane in clamping position within the slot in the base.
